Attorney

Patented Dec. 6, 1927.

UNITED STATES PATENT OFFICE.

FRANK S. SAXTON, OF BLISSFIELD, MICHIGAN.

APPAREL RACK.

Application filed January 27, 1927. Serial No. 163,953.

My invention has for its object to provide a foldable rack that is particularly adapted for use in automobiles and the like, for supporting coats and other wearing apparel, the construction containing my invention being such that the hooks may be readily removed or replaced or may be readily pushed to one side to avoid engagement when passengers leave and enter the car.

10 The invention may be contained in racks of different forms and to illustrate a practical application of the invention, I have selected a clothes rack containing the invention as an example of such structures, and 15 shall describe it hereinafter. The rack selected for purposes of illustration is shown in the accompanying drawings.

Fig. 1 is a perspective view of the rack shown mounted in an automobile body. Fig. 2 is a side view of the rack, the hooks being shown open or separated from each other and in position for receiving wearing apparel and other articles. Fig. 3 illustrates the manner in which the hooks may be removed from the rack.

The rack shown in the drawing has a base or frame 1. The base 1 is provided with a pair of ears 2 located at the upper and lower ends of the base. They are each provided 20 with a pair of openings for receiving parts of the hooks. The base may be secured in position by screws that may be passed through the openings.

The hooks 3 are each provided with projecting lugs 4 and 5 that extend one upwardly and the other downwardly and are of a size so that they will fit the openings formed in the upper and lower ears 2 of the base 1. The lugs 4 and 5 are, preferably, 30 made cylindrical in form and pivot in the ears 2 of the base 1. The lugs 4 are made longer than the lugs 5 while the distance between the outer ends of the lugs 4 and 5 is somewhat greater than the distance between 35 the ears 2 of the base 1, whereby each hook may be secured in the base 1 by inserting the lug 4 in the upper of the ears and then the lug 5 may be inserted in its associated opening in the lower ear. The lengths of 40 the lugs 4 and 5 are determined by the portions 6 and 7 that extend to the hooks. If desired the lugs 4 and 5 may be continued so as to form the bar 8 to which the hook 3 is connected by the portions or arms 6 and 45 7 and by the part 9. These parts are, pref-

erably, formed integral and their shapes may be varied as may be desired, provided the lengths of the lugs 4 and 5 have lengths that differ and the location of the part 7 is such as to support each hook 3 and so as to hold the lug 4 in the upper ear 2 of the base.

In order to yieldingly retain the hooks 3 in their position, and in order to prevent rattling of the hooks when the automobile is driven along the road, springs 10 are located intermediate the portions 6 and the upper ear 2 of the base 1. The springs 10 will operate to hold the lugs 5 in the lower ear and also prevent the hook 5 from being jounced out of the openings in the lower ear. The hooks, however, may be easily removed by pushing the hooks upward against the yielding resistance of the springs 10 until the lugs 5 are pushed out of the lower ear, whereupon the hook 3 may be tilted slightly so as to allow the hook to move downward, whereupon the lug 4 may be drawn from the upper ear. This is shown in Fig. 3.

The invention thus provides a means whereby the hooks may be placed flat against the wall of the car and thus out of the way, or, if desired, the hooks may be readily removed from the base leaving the base in position for reconnecting the hooks thereto when it is desired to place in the car a means for supporting wearing apparel. The invention finds a great advantage, particularly, when a tour is being taken by the passengers of the car and the hooks are used for supporting coats, etc.

I claim:

In an apparel rack, a base having a pair of ears located at the ends of the base, a hook having lugs in axial alignment and for pivotally supporting the hook in the ears of the base, the upper of the said lugs being longer than the lower of the lugs whereby the hook may be readily connected to and removed from the base, a compression spring surrounding the upper of the lugs and located intermediate a portion of the hook and the upper ear for yieldingly resisting the upper movement of the hook relative to the base and maintaining a part of the hook at the upper end of the lower lug in contact with the lower ear of the base.

In witness whereof I have hereunto signed my name to this specification.

FRANK S. SAXTON,
